CLAIM

The ornamental design of a swivel clip air connector, as shown and described.

DESCRIPTION

FIG. 1 is a perspective view of the invention.
FIG. 2 is a rear elevational view of the invention.
FIG. 3 is a left side elevational view of the invention.
FIG. 4 is a top plan view of the invention. The bottom view is a mirror image thereof.
FIG. 5 is a right side elevational view of the invention; and, FIG. 6 is a front elevational view of the invention.

1 Claim, 3 Drawing Sheets(56)
